UNITED STATES PATENT OFFICE.

WARREN HILL, OF TOWANDA, PENNSYLVANIA.

MOWING-MACHINE.

SPECIFICATION forming part of Letters Patent No. 330,116, dated November 10, 1885.

Application filed August 23, 1884. Serial No. 141,306. (No model.)

To all whom it may concern:

Be it known that I, WARREN HILL, of Towanda, in the county of Bradford and State of Pennsylvania, have invented a new and 5 Improved Mowing-Machine, of which the following is a full, clear, and exact description.

The object of my invention is to provide certain new and useful improvements in center-cut mowing-machines, whereby undue 10 pressure on the cutter-bar is prevented, the construction of the machine simplified, and all parts improved.

The invention consists in a mowing-machine provided with sleeves on the ends of the axle, 15 which sleeves are provided with downwardly-projecting arms with which the draft-pole is connected, and with downwardly and outwardly inclined arms on which a cross-bar rests, which, with the axle, supports the frame 20 containing the gearing and shafting.

The invention also consists in numerous other devices, details, and combinations of the same, as will be fully described and claimed hereinafter.

Reference is to be had to the accompanying 25 drawings, forming part of this specification, in which similar letters of reference indicate corresponding parts in all the figures.

Figure 1 is a plan view of my improved 30 mowing-machine, parts being broken out and others shown in section. Fig. 2 is a longitudinal sectional elevation of the same. Fig. 3 is a rear view, parts being broken out. Fig. 4 is a longitudinal view of the front supporting-bar of the frame. Fig. 5 is a side view of 35 the middle standard of the frame for the operating mechanism. Fig. 6 is a side view of the end hanger of the same. Fig. 7 is a sectional plan view on the line $x-x$, Fig. 3. Fig. 40 8 is a cross-sectional view of the runner.

The driving-wheels A A are either rigidly mounted on the shaft B or are provided with clutches, by means of which the shaft is revolved by the said wheels. On the shaft or 45 axle B a clutch-collar, B', is formed, which is adapted to engage with a clutch, C, formed on a sleeve, C, loosely mounted on the shaft B, on which sleeve C a flanged circular disk, D, is formed, having cogs formed on the inner 50 surface of the flange, the said cogs engaging with a pinion, E', on a shaft, E, on which is

also mounted a cog-wheel, E², engaging with a pinion, F', on a shaft, F, on one end of which is mounted a wheel or disk, G, provided with an eccentric or crank-pin. The shaft E is 55 journaled in the top of a standard, H, through which the shaft or axle B passes at the rear of the base of the said standard, and the front part of the base of the said standard is held by a clevis, H', on a transverse bar, J, in front of 60 and a short distance from the axle or shaft B. Adjoining one wheel a hanger, L, is hung on the axle or shaft B, and is connected by two transverse ribs or bars, L', with the base of the standard H. On the bars L' a standard, K, is 65 formed, in which the outer end of the shaft E is journaled. The shaft F is journaled in the bottom of the standard H and in the hanger L. The standard H, the standard K, the hanger L, and the bars or ribs L', are all firmly 70 united in a suitable manner, and form a strong solid frame, which rests on the axle and is also supported by the above-mentioned bar J. On the back of the above-mentioned frame a bar, M, is held to slide parallel with the 75 axle by pins passing through slots in the said bar M into the base of the standard H and into hanger L. From the said bar M two pins, m, project on the opposite sides of the cam-lever N, adapted to swing in a vertical plane and projecting upward, whereby by throwing the said cam-lever N in one direction or the other the bar M is shifted. The bar M is provided, on that end opposite the one provided with the pins m, with a 80 hook, m', which passes into a notch or recess in the sleeve C, whereby the sleeve C and the clutch C' on the same can be shifted toward or from the rigid clutch-collar B' on the shaft or axle. Adjoining the hub of each wheel a 85 sleeve, O, is loosely mounted on the shaft or axle, from each of which sleeves an arm, O', projects downward, and an arm, O², is inclined downward and outward, the said arms O² being each provided on the upper edge 90 with an upwardly-projecting eye, P, in which the hook ends J' of the above-mentioned bar J are held loosely, and each arm O² is provided on its outer surface, at the bottom end, with two transverse lugs, P', through which 95 bars Q are passed and held in place by means of pins P². On the lower ends of the bars Q 100

shoes R are held, which are provided with standards R'. Each shoe rests upon a runner, S, having a standard, S', the said runners being horizontal from the rear end to the standards S', and then bent outward and upward. 5 Bolts s are passed through the standards S' of the runners, and the standards R' of the shoes for holding the shoes at the desired elevation above the runners, whereby the finger-bar will be held a corresponding distance above the ground. Each shoe is provided with a screw, R³, which works in a screw-threaded aperture in the same, with its head below the lower surface of the shoe and resting 10 in a seat in the upper surface of the runner, as shown in Fig. 2. The said screw is adjusted so that its head projects a greater or less distance from the bottom of the shoe, according to the distance that the shoe is adjusted 15 above the runner. The runner is made very narrow, and decreases in width from its top to its bottom surface, so as to spread the grass more readily. On one shoe a bell-crank lever, T, is pivoted, which has one end connected with the cutter-bar T' and the other end connected by a connecting-rod, I, with the crank-pin G² on the disk G on one end of the shaft F. The draft-pole U is provided on its rear end with two outwardly-curved arms, V, 20 united by a brace-rod, V', and resting against the inner surface of the downwardly-projecting arms O' of the sleeves O. Bolts W are passed through the longitudinal slots o in the arms O', through the curved arms V, and 25 through plates or disks a, having their inner surfaces serrated and resting against the outer transversely-serrated surfaces of the arms O'. Suitable nuts are mounted on the bolts W for drawing them up tightly and jamming the 30 plates a against the arms O', thus holding the ends of the curved bars or arms V a greater or less distance below the shaft or axle B. If desired, any other suitable device can be provided for adjusting the bars or arms of the 35 draft-pole higher or lower. The horses pull on a double-tree, b, resting against the bolt c on the top of the pole. A hook, d, held on the double-tree b, is connected by a rod, e, with a clevis, f, passed through apertures in the base 40 of the standard H. Grass-rods l extend from the shoes S to the bars V.

The operation is as follows: Motion is transmitted from the axle or shaft B through the internally-cogged wheel D to the pinion E', the 45 cog-wheel E', the pinion F' on the shaft F, the end disk, G, the connecting-rod I, and the bell-crank lever T to the cutter-bar T'. The frame of the operating mechanism is supported, in part, by the cross-bar J, the ends of which are 50 held loosely in the eyes P in the arms O' of the sleeves O. If one end of the machine is raised more or less than the other, on account of unevenness of the ground or for other reasons, the machine will not be strained unduly or 55 broken, nor will the working of the knife be interfered with, as the ends of the said bar J are held loosely in the apertures in the arms 60

O². At the same time much of the weight of the operating mechanism is taken from the axle and transmitted by means of the said bar 70 to the cutting device. The draft is not directly from the axle, but from points a greater or less distance below the axle—that is, from the arms O'—and thereby the draft-pole has a tendency to raise the cutter-bar and the 75 shoes without any downward pressure on the pole, as is the case with all under draft applied to center-cut machines made heretofore, and prevent their digging into the ground, which is the great difficulty in center-cut 80 mowing-machines. The finger-bar and cutter-bar can easily be adjusted to cut the grass at the desired height above the ground. If the horses pull the machine forward too forcibly, they swing the lower ends of the arms O' 85 toward the front, and thereby the pole U will also be moved toward the front, and for an instant the bolt c will be slightly in front of the double-tree b. The strain on the double-tree b will then be transmitted through the hook 90 d, the connecting-rod e, and the clevis f to the standard H, and by acting on the same will press the arms O² downward, thereby swinging the arms O' backward again, and bringing all the parts into their normal position. 95 The machine is thus self-adjusting in relation to its draft. The lever N, for stopping and starting the machine, can easily be shifted by the person occupying the seat. The weight is carried directly by the axle, and none is 100 brought to bear upon the pole. The weight of the frame and machinery and the downward pressure of the machinery while working are divided equally between the two arms Q, which gives an even pressure on both ends 105 of the cutter-bar, which no other machine has, except where the pressure is transmitted from the pole, which I wish to avoid. The centers of the shafts B F and the knife-bar pin should be on one line, as shown by dotted lines in 110 Fig. 2, for by arranging the parts in this manner the operation of the knife is not affected when the knife is raised more or less.

Having thus described my invention, what I claim as new, and desire to secure by Letters 115 Patent, is—

1. In a mowing-machine, the combination, with the sleeves O O, mounted on the axle or driving-shaft and provided with the downwardly-projecting arms O' O' and the forwardly-extending arms O² O², of the cross-bar J, resting on the arms O², and an iron frame carrying the operating mechanism, the said frame resting partly on the axle and partly 120 on the bar J, substantially as herein shown 125 and described.

2. In a mowing-machine, the combination, with the axle or driving-shaft, of the sleeves O O, mounted on the same, and having downwardly-projecting arms O' O' and forwardly-extending arms O² O², provided with eyes P, 130 the transverse bar J, having hooks J' at the ends, the hooks J' being passed through the eyes P, and an iron frame resting on the axle 135

or driving-shaft and on the bar J, and carrying the operating mechanism, substantially as herein shown and described.

3. In a mowing-machine, the combination, 5 with the axle or driving-shaft B, of the sleeves O O and arms O' O' and O² O², the cross-bar J, resting on the arms O², the standard H, and the hanger L, connected by bars L', the hook-clevis H', holding the base of the standard H 10 on the bar J, and shafts journaled in the standard H, in the standard K, on the bars L', and in the hanger L, substantially as herein shown and described.

4. In a mowing-machine, the combination, 15 with the axle or driving-shaft, of the sleeves O O, having arms O' O' and O² O², the bar J, a frame supported by the axle and the bar J, the sliding bar M on the said frame, the pins m on the said bar, the cam-lever N, and the 20 sliding cog-wheel D, mounted on the axle and provided with a clutch-collar, which sliding cog-wheel is adapted to be shifted by the bar M, substantially as herein shown and described.

5. In a mowing-machine, the combination, 25 with the axle or driving-shaft B, of the sleeves O O, having arms O' O' O² O², the bar J, a frame supported by the bar J and the axle B, the clutch-collar B', the pinion E', engaging with the cog-wheel D and mounted on the shaft

30 E, the cog-wheel E' on the shaft E, the pinion F', mounted on the shaft F and engaging with the cog-wheel E², the crank-wheel G on the end of the shaft F, the connecting-rod I, connected with the crank-wheel G, and a cutter-bar operated from the said rod I, substantially as herein shown and described.

6. In a mowing-machine, the combination, 35 with the axle or driving-shaft B, of the sleeves O O, having arms O' O², the bars Q, held in lugs P' of the arms O², and the shoes held on the lower ends of the bars Q, substantially as herein shown and described.

7. In a mowing-machine, the combination, 40 with the driving-shaft or axle B, of the sleeves O, having arms O' and O², the finger-bar at-

tached to the arms O² by means of the bars Q, the pole U, and the rear arms, V, of the same, connected with the downwardly-projecting arms O' of the sleeves O, substantially as herein shown and described.

50

8. In a mowing-machine, the combination, with the driving-shaft or axle B, of the sleeves O, having arms O' and O², the pole U, having arms V, and nuts and bolts for holding the rear ends of the arms V adjustably on the 55 downwardly-projecting arms O' of the sleeves O, substantially as herein shown and described.

9. In a mowing-machine, the combination, 60 with the driving-shaft or axle B, of the sleeves O, having the arms O² and the downwardly-projecting arms O', provided with vertical slots and with transverse serrations on the outer sides, the pole U, the arms V, the serrated disk a, and the bolt W, passed through 65 the slots in the arms O', the arms V, and the disk a, substantially as herein shown and described.

10. In a mowing-machine, the combination, 70 with the shoe R, having the standard R', of the runner S, having the standard S', the bolt s, passed through the standards S' and R', and of the adjusting-screw R³ in the shoe, substantially as herein shown and described.

11. In a mowing-machine, the combination, 75 with the driving-shaft or axle B, of the sleeves O, having arms O' and O², cutting devices supported by means of the rods Q on the arm O², the pole U, having arms V, connected with the arms O', the bolt c on the pole, the double-tree b, the hook d, the connecting-rod e, and the clevis f, connected with the standard H, resting on the axle and on the bar J, held at its inner ends in the arms O², substantially as herein shown and described.
